H. S. HART

DUMP CAR DOOR LOCKING AND RELEASING ATTACHMENT

Filed Jan. 3, 1922

UNITED STATES PATENT OFFICE.

HARRY S. HART, OF CHICAGO, ILLINOIS.

DUMP-CAR-DOOR LOCKING AND RELEASING ATTACHMENT.

Application filed January 3, 1922. Serial No. 526,588.

To all whom it may concern:

Be it known that I, HARRY S. HART, a citizen of the United States, residing at Chicago, in the county of Cook and State 5 of Illinois, have invented certain new and useful Improvements in Dump-Car-Door Locking and Releasing Attachments, of which the following is a specification.

This invention relates to dump car door 10 locking mechanisms, and particularly to that type of such mechanism in which one or more latches are employed for holding the cargo-discharging door closed against the internal load imposed upon it until such 15 time as may be desired to discharge the contents.

Heretofore it has been proposed to employ latches for the purpose stated, but such latches have been so arranged as to involve 20 separate local manipulation in engaging them with the door, introducing the dogging device or chock behind each latch to prevent its displacement under the vibration of travel, and to withdraw it for re- 25 leasing the door at the place of intended discharge. Moreover, manipulation of these previously known arrangements has necessitated the presence of the operator in a 30 position of danger. Moreover, releasing manipulation of such previously known devices, owing to presence of separately displaceable chocks, the disposition of the 35 centers of movement of the latches, the necessity of acting directly upon them, and the absence of power developing means, has 40 been time consuming and difficult of accomplishment, and required the presence of the operator in a position of danger from the discharging cargo.

One object of the present invention is to 45 provide a locking means for the latch or latches of a dump car door, which will automatically enter into and retire from locking position by the latching and unlatching of the door; and which, preferably, is in position to assist the latching action by its own gravitation.

Another object is to adapt the latch locking means to serve as a power developing 50 actuator for forcibly withdrawing the latch, and, preferably, also for forcing it to its seat against the door part with which it engages; the movements of the actuator so nearly approaching parallelism with the 55 engaging faces of the latch and door as to greatly increase the power of the latching

action; and the pivot of the latch being located to develop a substantially vertical component in latching and unlatching movements, which facilitates withdrawal, 60 and, under the power of the actuator, forces the door to its seat after initial engagement by the latch.

Still another object is to adapt the latch locking and forcing means to serve a pair 65 of latches simultaneously; also to insure full movement in each latch.

Still another object is to adapt a latch actuator, which functions as above set forth, to be manipulated, particularly in the door 70 releasing direction, from a vantage point out of the path of cargo discharge; also to effect such remote manipulation through the instrumentality of a lever arm that greatly reduces the effort required.

Still another object is to provide a detent 75 which will hold the latch and its locking means in withdrawn position until the door approaches closed position, and will thereupon be released, by the door, to automatic 80 latching and locking movements; the preferred method of realizing this object involving merely the original withdrawal movement of the latch or latches which automatically admits the detent into the path 85 of its latch, there to remain and hold the latch and its combined locking member and actuator in retracted position until displaced by the door to release said parts to automatic locking action.

The preferred embodiment of the invention is shown in the accompanying drawings and set forth in detail in the following description, but it is to be taken as illustrative of the invention rather than definitive of its scope, and the invention is to be understood as including any device coming within any of the foregoing statements of operative principle, and within the terms of any of the subjoined claims.

In said drawings—

Figures 1 and 2 are, respectively, a side elevation and a vertical transverse section through a portion of a freight car to which an embodiment of the invention is applied.

Figure 3 is a side elevation of the latching, locking and actuating mechanism on an enlarged scale; the unlocked and unlatched positions of the parts as well as the dogging 105 positions of the detents being shown in dotted lines.

Figure 4 is an end elevation of the lock-

ing and latching mechanism, with the appurtenant parts of the car structure in section.

5, represents a portion of a car body, 6 the dumping doorway thereof, and 7 the door for closing said doorway. Door 7 is commonly hinged at 8 and retained in closed position against the load of its superposed cargo by a locking mechanism engaging some portions of the door, such, for instance, 10 as protruding ends of its cleats 9.

To hold the door closed, the present invention proposes to use a latch or latches 10 pivoted at 11, preferably to the outer side wall of the car, in position to engage beneath 15 the cleat or cleats 9 when the door is closed. Pivot 11, will preferably be in a vertical line lying to one side of the door part which the latch engages, so that retracting movement will involve, at least initially, a downward component that reduces 20 the effort required to withdraw the latch, and an upward component in the latching movement which causes the latch to seat the door.

25 To lock the latch, toggle arms 12, 12 are employed, pivoted together at 13 and pivotally connecting a point 14 on a latch with a suitable opposing support, which, in cases where two latches are used, will be the corresponding 30 point 14 on the other latch so that the two latches become reciprocal in their action and mutually self sustaining through the medium of the toggle connection. Toggle arms 12 act in a vertical plane 35 so that their gravitation assists in seating the latches. They have a limiting lug 15 that arrests their downward movement and reduces their joint 13 to the nature of a knuckle-joint, but this lug is positioned to 40 permit the joint to descend to or slightly below parallelism of the links, so that a definite upward thrust perpendicular to any unlatching impulse of the latches must be exerted to unlock the door; and when approaching 45 or leaving their locked position the action upon the latches is so nearly parallel to the engaging faces of the latches and door as to greatly reduce the force required for the action. Each latch 10 has a 50 stop 16 that encounters a fixed part of the structure at the end of withdrawing movement, so that the latch first reaching its limit of movement serves as a fixed anchorage from which the toggle may react upon the 55 other latch. In latching movement, attainment of its seat against the door enables it to serve the toggle similarly to insure full throw in the other latch.

60 To adapt the toggle actuator for manipulation from a vantage point of safety, one or both of its links are constructed with purchase lugs 17 adapting it to receive a leverage arm 18 extending in direction and distance that adapt it for the service stated.

65 To detain the latches, as well as their lock-

ing means and actuator, in unlocked and unlatched position, a dog 19 for each latch is pivoted at 20 in position to drop into the path of the toe 21 of the latch, as shown in dotted lines in Figure 3, a stop 22 on 70 the dog engaging a fixed part of the structure to limit its downward movement, and in order that the latch and actuator may be released to automatic latching and locking action by the mere act of throwing the 75 door to closing position, said dog is in the path of the door when in detaining position. When released, the toggle links develop a very prompt and positive latching movement without the use of springs or other 80 readily impaired instrumentality, and the whole arrangement is of simple construction and operation and peculiarly adapted for embodiment in substantial and durable 85 form.

I claim:

1. In a dump car door locking mechanism, a latching member, and a locking means entering into and retiring from locking position by the latching and unlatching of the door, said latching member having a support located to prevent transmission of the load of the door to said locking means.

2. In a dump car door locking mechanism, a latching member having a support which takes substantially the entire load transmitted from the door to the latching member, and a locking means free from the load of the door, but entering into and retiring from locking position by the latching and unlatching of the door, and having connections with the latch through which it positively imparts latching and unlatching movements to the latter.

3. In a dump car door locking mechanism, a pair of latches having supports which take up the entire load imparted from the door to the latches, and a locking means serving in common for both latches and moving into and out of locking position by the latching and unlatching of the door, said locking means being free from the load of the door.

4. In a dump car door locking mechanism, a latch, a support for said latch located in the line of bearing of the door upon the latch, and a toggle controlling said latch in a direction transverse to said line.

5. In a dump car door locking mechanism, a pair of latches, and a toggle connecting said latches and moving into and out of locking position by the latching and unlatching movements thereof.

6. In a dump car door locking mechanism, a latch, and a toggle controlling said latch assuming thrust-resisting position when the latch is in engagement with the door, said latch having a support substantially in vertical alignment with the bearing of the door against the latch.

7. In a dump car door locking mechanism, a latch having a face through which it engages the door and moving approximately in the plane of said face as it assumes latching relation to the door, and a toggle controlling said latch approximating its straight line position when substantially parallel to said plane. 45
8. In a dump car door locking mechanism, 10 a latch, toggle links connected with said latch and adapted to control the movements thereof, and means carried by a link for engagement of a lever arm through which to actuate the toggle links. 50
9. In a dump car door locking mechanism, 15 a pair of latches, toggle links connecting said latches and adapted to control the movements thereof, and a stop on each latch arresting it at the end of its unlatching movement and thereby adapting it to serve as an anchorage for the toggle links in completing the movement of the other latch. 55
10. In a dump car door locking mechanism, 20 a pivoted latch moving to engage and release the door in a direction substantially transverse to the movement of the door, and having its pivot located to develop in its said movement a component substantially coincident with the closing movement of the door, and a toggle controlling said movements of said latch. 60
11. In a dump car door locking mechanism, 25 a latch moving into and out of engagement with the door, and a dog automatically moving into the path of the latch and detaining it in unlatched position. 65
12. In a dump car door locking mechanism, 30 a latch moving into and out of engagement with the door, and a dog automatically moving into the path of the latch and de- 70
- taining it in unlatched position; said dog in its detaining position lying in the path of the door and being automatically displaced by the closing of the door. 75
13. In a dump car door locking mechanism, 45 a latch, a locking means for said latch moving into and out of locking position by the latching and unlatching of the door, and a dog moving automatically into the path of the latch at the unlatching of the door, thereby detaining the latch and locking means. 50
14. In a dump car door locking mechanism, 50 a latch, a locking means for said latch moving into and out of locking position by the latching and unlatching of the door, and a dog moving automatically into the path of the latch at the unlatching of the door, thereby detaining the latch and locking means; said dog in its detaining position being in the path of the door and being displaced by the closing of the door. 55
15. In a dump car door locking mechanism, 55 a latch having a swinging movement into and out of latching position and having a hook by which it engages the door, and a pivoted dog movable into the path of the hook on the latch at the time of unlatching. 60
16. In a dump car door locking mechanism, 60 a latch having a swinging movement into and out of latching position and having a hook by which it engages the door, and a pivoted dog movable into the path of the hook on the latch at the time of unlatching; 65 said dog having a stop for arresting its movement when it reaches detaining position. 70
17. In a dump car door locking mechanism, 70 a latch having a swinging movement into and out of latching position and having a hook by which it engages the door, and a pivoted dog movable into the path of the hook on the latch at the time of unlatching; 75 said dog having a stop for arresting its movement when it reaches detaining position. 80

Signed at Chicago, Illinois, this 29th day of December, 1921.

HARRY S. HART.
